CONTAINER

Application filed May 14, 1930. Serial No. 452,177.

This invention relates to sanitary appliances and more particularly to an improved container for domestic refuse or garbage.

As is well known, the disposal of household refuse, especially garbage, involves a great deal of inconvenience to the householder and housewife, due to the fact that it must be collected in a container of metal and the like, and then transferred to a garbage wagon for removal from the premises. Such containers rapidly became fouled with use, and vigorous cleaning is required at frequent intervals to maintain them in as relatively inoffensive condition as possible.

15 In large municipalities where daily removal of household waste material is generally required by municipal ordinances, considerable trouble and inconvenience is encountered in packaging or otherwise preparing the garbage for disposal. The use of newspapers, paper bags, or other absorbent containers, requires an excessive amount of material in order to prevent the disruption of the parcel or bundle when it contains wet or sloppy material.

It is an object of this invention to provide a sanitary, moisture-proof container for household refuse, which is readily and easily disposed of.

20 Another object of this invention is the provision of such a container, adapted to be used as a sanitary liner for a garbage receptacle.

Still another object of this invention is the provision of a sanitary, moisture-proof liner or container for garbage receptacles 35 provided with supporting extensions or tabs, whereby the container is adapted to be supported in the receptacle by the cooperative action of the cover on the tabs.

Yet another object of this invention is the provision of a moisture-proof liner for garbage receptacles, which is impregnated with deodorants and antiseptic materials.

40 A further object of this invention is the provision of an article of the character described which is adapted to be packaged for sale as a unitary article and which is easy to manufacture and is of such low cost as to 50 render it susceptible of use and subsequent

destruction without involving high replacement costs.

These and other desirable objects and advantages will be described in the following specification and illustrated in the accompanying drawing, in which preferred embodiments are shown by way of example, for since the underlying principles may be incorporated in a variety of useful devices, it is not desired to limit the invention in its useful 55 applications to the devices shown, except insofar as such limitations are clearly imposed by the appended claim.

In the drawing, like numerals refer to similar parts throughout the several views, of 60 which

Fig. 1 is a perspective view of a container embodying the principles of the present invention;

Fig. 2 is a perspective view of a modification of the device shown in Fig. 1;

Fig. 3 is a diagrammatic showing of the device shown in Fig. 1 in position in a garbage receptacle, parts of the receptacle being 65 broken away to show the relation of the liner to the container, and

Fig. 4 is a view similar to Fig. 3 in which the modified form of supporting tabs of Fig. 2 is used.

The container or liner comprises a bag-shaped device having a body portion 1 of any suitable configuration, and an integral bottom portion 2. As shown, the container is rectangular in cross-section, but, as above intimated, it may have any desired cross-section. 80

The body portion of the container is provided at its upper open end with a plurality of equally spaced integral tabs or extensions 85 of reduced width, which are of substantial length, the tabs shown being designated, respectively, by the numerals 3, 4, 5 and 6. These tabs are adapted to be folded over the top rim of a container 7, such as the well-known garbage pail or can used for households, and are held in position by the cover 8 of member 7. The even spacing of the supports gives an equal distribution of holding strength over the periphery of the liner 90 and thus prevents tearing. 95

In ordinary use the container is opened up and inserted into its receptacle, the sides of the bag being conformed to the inner wall of the receptacle, and the supporting tabs bent 5 outwardly and downwardly, as shown.

When refuse is put into the receptacle and the cover placed in position, the supporting tabs are firmly gripped and the liner prevented from sagging or collapsing.

10 When the proper time for the disposal of the refuse material comes, the liner containing the material is removed from the receptacle and top is tied firmly or otherwise suitably secured. The package of refuse material may then be disposed of in any desired fashion without involving the soiling of one's hands or clothes, and without danger of disruption due to the effect of water on the bag.

20 The modification shown in Figs. 2 and 4 comprehends the use of a plurality of tabs 3', 4', 5' and 6', which are collectively of the same circumference as the body of the container. This construction allows of the folds 25 of material being turned inwardly on each other to permit the formation of a top liner portion having a plurality of thicknesses whereby the container may be used in an open receptacle without exposing the contained detritus to the atmosphere and thereby prevent access of flies and other insects in addition to preventing the dissemination of undesirable odors. Such a container may 30 be secured with twine or any suitable fastening material and disposed of as desired.

The action on paper or cardboard of the fluid or pasty matter which makes up a considerable portion of ordinary garbage is very annoying, due to the absorptive capacity of 40 the paper material for moisture. This results in rapid deterioration of the package or bundle, and its disruption, with consequent undesired exposure of its contents.

The article of the present invention is preferably made of suitable water-proof material 45 such as paper of kraft or manila type, which has been treated with wax or oil to impregnate the fibres, thereby imparting the property of moisture-repelling to the paper. In 50 addition to its moisture repelling property, the wax or oil used may serve as a vehicle for antiseptics and/or deodorants for the purpose of minimizing or preventing bacterial growth within such packages if the 55 contents are permitted to stand for any considerable length of time. The materials used for antisepticizing and deodorizing are well known and it is intended that all such materials which are suitable for use in an article 60 of the character described be comprehended within the spirit and scope of the present invention.

The weight of paper used will depend primarily upon the size of the garbage container 65 or liner. For example, a liner adapted for

use in the small garbage pails commonly sold for use in small apartments and the like, could be of relatively light weight stock without any danger of disruption due to excess weight of the contained materials.

Where the container is of large size, such, for example as the galvanized iron cans used in hospitals, hotels and institutions generally, a larger liner of course will be necessary and the material of the liner will be accordingly varied in order to provide the requisite strength, which, as above noted, in addition to the moisture-proofing advantages, is distinctly a function of the weight of the paper material generally.

70 The treated paper container can be used without being inserted in a pail or covered can. Where such use is contemplated, the strength of the bag can be varied to suit, as already pointed out. When so used, the container may readily be placed on the drain-board of a sink and the waste material dumped therein, after which the whole package is closed up and disposed of.

75 A particularly advantageous feature of the present invention resides in its ability to withstand the relatively high degree of heat and moisture, as is necessary in sterilizing apparatus of the type used in hospitals. By sterilizing these containers, they are adapted 80 for use generally about hospitals, and especially for the purpose of holding waste surgical dressings, which at present are placed in enamel pans or basins. These basins, with their contained material, must then be covered with a towel and removed and placed in a large container, the basin requiring much 85 cleaning before it can again be used. By the use of the antisepticized containers described herein, the used material, such as surgical 90 dressings, may be practically deposited in a container of suitable size, which is immediately sent to the furnace or incinerator for disposal thereby obviating the necessity of 95 dirtying metallic basins and subsequently 100 cleaning them.

105 In homes provided with ranges of the coal burning type, or furnaces, the liner with its contained garbage may be incinerated without bothering to keep the material standing around until the municipal authorities remove it in the ordinary course of their routine.

115 Such incineration is the ideal method of 120 disposing of the relatively small quantities of garbage, as it aids in keeping the premises clean, and also serves to prevent the multiplication of the domestic house-fly by getting rid of one of its breeding places.

125 The use of such a moisture-proof liner for garbage cans or pails, assists materially in 130 keeping the latter in a clean, sweet condition by preventing the access of detritus and moisture to the walls of the can or plate. As already stated, the metal containers used for holding garbage material are almost impos-

sible to clean thoroughly due to the oleaginous nature of the waste material which forms a hard resistant coating on the interior of the walls of the can, which coating serves 5 as an adhesive and keeps or retains the particles of decomposable matter under proper conditions for decomposition. When mold growth sets in, the can, lined with the improved container of the present invention, is 10 not musty or sour, odors emanating from the decomposing waste materials, which are highly offensive, being retained in the improved container.

Where incineration is neither practicable 15 nor desired, the bags of garbage may be buried or otherwise disposed of, the material of the bag or liner gradually decomposing. This decomposition is relatively slow, so that the contents will have had ample time for 20 degeneration before they are exposed to the atmosphere.

It will now be seen that there has been provided an improved container for waste material such as garbage and the like, which is 25 highly efficient, being moisture-repellant and odorless, and which is available at such a low price as to enable it to be thrown away without involving any great expense. These con-

tainers are available in a variety of sizes, the material used in their manufacture being suitably varied to meet the conditions of use to which it is to be subjected.

What is claimed is:

An improved preformed moisture and fly-proof bag-shaped garbage container adapted to be inserted into and conformed to the inside of a cylindrical garbage can forming a liner therefor, said container being made of a freely flexible water-proof fabric and comprising a preformed bag having a substantially square bottom together with unitary sides severally terminating in freely flexible but not self sustaining tab portions, the tab 70 portions of the sides being of a size sufficient to fold toward each other and completely close the top of the container to prevent ingress of insects and also to prevent the liberation of odors and being further adapted to be bent 75 over the rim of a can in which the bag is inserted and conformed as a liner whereby to form a substantially continuous depending sectional apron for the rim, the said apron being adapted to coact with a superimposed 80 and fitted cover for the can to be retained 85 thereby and to seal the can and its contents.
